UNITED STATES PATENT OFFICE.

ANNIE WATKIN, OF PHILADELPHIA, PENNSYLVANIA.

DESIGN FOR A KNIFE-CLEANER.

SPECIFICATION forming part of Design No. 24,969, dated December 10, 1895.

Application filed November 1, 1895. Serial No. 567,654. Term of patent 7 years.

To all whom it may concern:

Be it known that I, ANNIE WATKIN, a citizen of the United States, residing in Philadelphia, Pennsylvania, have invented a certain new and useful Design for Knife-Cleaners, of which the following is a specification.

My design for a knife-cleaner is fully shown in the accompanying drawings, in which—

Figure 1 represents a perspective view of said knife-cleaner. Fig. 2 is a side view of the same, and Fig. 3 is an end view.

The design comprises the pad A and handle B, both of which are of general rectangular form, the pad A flaring from top to bottom at each end, so as to form the bevel ends *a* and the feather edges *b* at the lower corners.

The handle B is, at the base, of the same dimensions as the top of the pad A, the ends *d* of the handle being straight, but the sides *f* flaring slightly outward from bottom to top. ²⁰

The top *g* of the handle is rounded both longitudinally and transversely.

I claim—

The design for a knife cleaner, substantially as described and shown. ²⁵

In testimony whereof I have signed my name to this specification in the presence of two subscribing witnesses.

ANNIE WATKIN.
